HAMMER SHROUD FOR REVOLVERS

John M. McNally, Newington, Conn., assignor to
Colt's Manufacturing Company, Hartford,
Conn., a corporation of Connecticut

Application November 3, 1949, Serial No. 125,311

3 Claims. (Cl. 42—66)

1

The invention relates to a hammer shroud for a revolver and to the combination of the hammer shroud with the revolver.

More particularly, the invention relates to a hammer shroud for a revolver in which the hammer extends beyond the frame and is relatively movable in an arcuate path and has a cocking projection. A revolver of the type described may be carried in a pocket of the user, ordinarily a law enforcement officer, and it is frequently necessary to quickly withdraw the revolver. When the revolver is so withdrawn, there is a tendency for the cocking projection on the hammer to engage a portion of the pocket, thus preventing the desired quick withdrawal and incidentally sometimes tearing the pocket. For a law enforcement officer any inability to quickly withdraw the revolver may lead to serious consequences.

In accordance with the invention a structurally separate shroud is provided which is attachable to the frame of the revolver and which is so constructed and shaped that it prevents the hammer from engaging the pocket with the above-described results. The hammer shroud has arcuate faces at the sides of the hammer, which faces generally conform to the path of movement of the outermost portion of the cocking projection on the hammer but are nevertheless spaced slightly inwardly from the said path so that the said projection is exposed sufficiently for any necessary manual engagement.

In the drawing I have shown in detail a preferred embodiment of the invention, but it will be understood that various changes may be made from the construction shown, and that the drawing is not to be construed as defining or limiting the scope of the invention, the claims forming a part of this specification being relied upon for that purpose.

Of the drawing:

Fig. 1 is a side view of a revolver and a hammer shroud therefor embodying the invention.

Fig. 2 is a fragmentary side view similar to Fig. 1 but with the left portion of the shroud omitted, a portion of the shroud being shown in section.

Fig. 3 is a fragmentary sectional view taken along the line 3—3 of Fig. 2.

Fig. 4 is an enlarged perspective view of the shroud.

Fig. 1 of the drawing shows a revolver of a well-known type, but it will be understood that this particular revolver has been selected merely for the purposes of illustration and that the in-

2

vention is generally applicable to any revolver wherein the hammer projects beyond the frame and is relatively movable in an arcuate path.

The revolver as shown comprises a frame 10 provided with a grip 12 and having a barrel 14 carried thereby. The upper rear portion of the frame has opposite parallel side faces. The cylinder as shown at 16 is rotatably mounted on a crane 18 which is pivotally connected to the frame in the usual manner so that the cylinder can be swung laterally, ordinarily toward the left, for loading the cartridges or for extracting the cartridge shells.

The frame 10 is provided with a trigger guard 20 within which is positioned a trigger 22. Pivotally mounted within the frame is a hammer 24, the hammer being provided with a firing pin 26 and with a cocking projection 28. The hammer 24 projects beyond the frame and is movable in an arcuate path. By means of conventional mechanism, not shown, movement of the trigger serves to index the cylinder for positioning an unfired cartridge and serves simultaneously to cock the hammer. Continued movement of the trigger releases the hammer to effect firing. By the engagement of the user's thumb with the cocking projection 28, the hammer may be manually moved independently of the trigger to a fully cocked position as shown by full lines 30 in Fig. 2, the cylinder being simultaneously indexed. The hammer is automatically latched in the fully cocked position and can be released by the trigger to effect firing.

A hammer shroud is provided which is separate from the frame 10 but which is attachable thereto. The hammer shroud may vary as to details, but it is preferably constructed and shaped as shown in the drawing. The hammer shroud comprises two similar transversely spaced longitudinal walls 30, 30 which are adapted to be located in fixed positions at opposite sides of the hammer 24. The walls 30, 30 of the shroud are shaped at their inner edges to approximately fit the immediately adjacent portion of the frame, and they are preferably provided with opposite parallel faces which are spaced to register with the parallel side faces of the frame as clearly shown in Fig. 3. The space between the walls 30, 30 is outwardly exposed and the said walls are outwardly exposed at their outer edges and are shaped to provide arcuate faces which generally conform to the path of movement of the outermost portion of the cocking projection 28 on the hammer. The said outer faces of the walls 30, 30 while generally conforming to the said path

of arcuate movement are nevertheless spaced slightly inwardly therefrom, thus enabling the projection 28 to remain exposed sufficiently for manual engagement so that independent manual cocking can be effected in the usual manner.

Preferably the walls 30, 30 of the shroud are connected with each other by an integral transverse connection 32 which extends between the said walls near the rear portions thereof. The said transverse connection 32 is adapted to be positioned at the rear of the hammer and is shaped to engage at its front with a rear portion of the frame.

Formed integrally with the walls 30, 30 of the shroud are laterally offset forward projections 15, 34, 34, these projections being spaced and shaped to engage the opposite lateral faces of the frame.

The said transverse connection 32 is provided with a longitudinal hole or aperture 36 for receiving a screw 38, the screw extending into a threaded aperture in the frame 10. Preferably the aperture 36 is countersunk or counterbored to receive the head of the screw. The said offset projections 34, 34 are provided with transverse holes or apertures 40, 40 for receiving screws 42, the screws extending into threaded apertures in the frame 10. Preferably the apertures 40, 40 are countersunk or counterbored to receive the heads of the screws.

With the shroud attached to the revolver as described, the hammer is entirely guarded except for the required slight exposure of the cocking projection 28 beyond the edge faces of the walls 30, 30. When the revolver is carried in a pocket of the user, it can be quickly and easily withdrawn without the possibility of the hammer catching in the fabric of the pocket to prevent withdrawal or to damage the pocket.

It will be seen that a hammer shroud embodying the invention is adapted for attachment to a previously or separately manufactured revolver, no change in the revolver construction being required other than the drilling and tapping of the necessary holes for the screws 38 and 42. If the conditions of intended use of the revolver should be changed so that the shroud is no longer necessary or desirable, the shroud can be readily removed.

What is claimed is:

1. For a revolver having a frame and having a hammer extending beyond the frame which hammer is relatively movable in an arcuate path and has a cocking projection, a shroud for the said hammer separate from and attachable to the said frame and having two similar transversely spaced longitudinal walls adapted to be located in fixed positions at opposite sides of the hammer, the space between the said walls being outwardly exposed and the said walls being shaped at their inner edges to approximately fit the frame and the said walls having exposed outer edges shaped to provide arcuate faces which generally conform to the path of movement of the outermost portion of the cocking projection on the hammer and which are spaced slightly inwardly from the said path so that the said projection is outwardly exposed for manual engagement, each of said walls having a laterally offset forward projection spaced from each other for engaging lateral faces of said frame.

5

4

2. For a revolver having a frame with parallel lateral faces and having a hammer extending beyond the frame which hammer is relatively movable in an arcuate path and has a cocking projection, a shroud for the said hammer separate from and attachable to the said frame and comprising two similar transversely spaced longitudinal walls and comprising laterally offset forward projections on the respective walls and also comprising an integral transverse connection between the said walls near the rear portions thereof, the said spaced walls being adapted to be positioned at opposite sides of the hammer and being shaped at their inner edges to approximately fit the frame and being shaped at their outer edges to provide arcuate faces which generally conform to but are spaced slightly inwardly from the path of movement of the outermost portion of the cocking projection on the hammer and the said laterally offset projections being spaced and shaped to engage the parallel lateral faces of the frame and being transversely apertured to receive attaching screws and the said transverse connection being positioned and shaped to engage at its front with a rear portion of the frame and being longitudinally apertured to receive an attaching screw.

3. The combination of a revolver having a frame with parallel lateral faces and having a hammer extending beyond the frame which hammer is relatively movable in an arcuate path and has a cocking projection, a shroud for the said hammer separate from the said frame and comprising two similar transversely spaced longitudinal walls and comprising laterally offset forward projections on the respective walls and also comprising an integral transverse connection between the said walls near the rear portions thereof, the said shroud walls being positioned at opposite sides of the hammer and approximately fitting the frame at their inner edges and being shaped at their outer edges to provide arcuate faces which generally conform to but are spaced slightly inwardly from the path of movement of the outermost portion of the cocking projection on the hammer and the said laterally offset projections of the shroud engaging the said parallel lateral faces of the frame and being transversely apertured and the said transverse connection of the shroud being positioned at the rear of the hammer and engaging at its front with a rear portion of the frame and being longitudinally apertured, and screws extending through the apertures in the forward projections and transverse connection of the shroud for attaching the said shroud to the frame of the revolver.
